CLAIM

The ornamental design for a water deflection shield for ventilator intake apertures, as shown and described.

DESCRIPTION

FIG. 1 is a top, front perspective view of a water deflection shield for ventilator intake apertures showing my new design;

FIG. 2 is a right side elevational view thereof;

FIG. 3 is a left side elevational view thereof;

FIG. 4 is a front elevational view thereof; and

FIG. 5 is a bottom plan view thereof.
